REFRIGERATION

Albert R. Thomas, Evansville, Ind., assignor to
 Servel, Inc., New York, N. Y. a corporation of
 Delaware

Application October 27, 1936, Serial No. 107,852

31 Claims. (Cl. 62—119.5)

My invention relates to refrigeration and more particularly a refrigeration system which makes use of evaporation of refrigerant in the presence of inert gas.

5 It is an object of the invention to provide an improved refrigeration system of this type having greater capacity and efficiency. I accomplish this in a manner which will appear as I describe and explain an embodiment of the invention in a refrigeration system which is generally like that described in U. S. Patent 1,609,334 granted Dec. 7, 1926, to von Platen and Munters, and as illustrated by the accompanying drawings, forming part of this specification, of which:

15 Fig. 1 is a vertical sectional view of an evaporator embodying the invention;

Fig. 2 is a more or less diagrammatic view with parts in vertical section illustrating a refrigeration system embodying the invention including the evaporator shown in Fig. 1;

20 Fig. 3 is a detail sectional view on line 3—3 in Fig. 2;

Fig. 4 is an enlarged view of a portion of the apparatus shown in Fig. 2;

25 Fig. 5 is a view like that of Fig. 2 illustrating a modification;

Fig. 6 is a front view with parts broken away of a refrigeration apparatus unit involving the parts and system illustrated in Fig. 2.

30 Fig. 7 is a rear view of the apparatus unit shown in Fig. 6;

Fig. 8 is a sectional view on line 8—8 in Figs. 6 and 7;

Fig. 9 is a sectional view on line 9—9 in Figs. 35 6 and 7;

Fig. 10 is a sectional view on line 10—10 in Fig. 9, so that this figure is substantially a top view of the unit; and

40 Fig. 11 is a chart showing the effect of variation in the slope of the piping in the evaporator and absorber.

In the system described in said patent granted to von Platen and Munters, refrigerant, such as ammonia, is expelled from solution in an absorption liquid, condensed, and conducted to a vessel, called an evaporator, which is in heat exchange relation with a body to be cooled. In the evaporator, the liquid refrigerant evaporates in the presence of an inert gas, such as hydrogen, which flows through the evaporator. The evaporation of the liquid refrigerant produces refrigeration, the heat of evaporation being transferred to the refrigerant from the body to be cooled which is in heat exchange relation with the 55 evaporator.

The amount of refrigeration produced depends upon the rate of heat transfer from the body to be cooled to the liquid refrigerant and the rate of evaporation of the refrigerant. The refrigeration temperature depends upon the partial pressure of the refrigerant vapor in the evaporator which in turn depends upon the rate of removal of the refrigerant vapor from the presence of the refrigerant liquid. It will now be understood that both the relationship of the refrigerant and the inert gas, and the heat transfer relationship between the refrigerant liquid and the body to be cooled are important. It is desirable that the relationship between the body to be cooled and the liquid refrigerant afford the greatest rate of heat transfer and that the relationship between the refrigerant and the inert gas afford the desired rate of evaporation.

Referring to Fig. 1, there is shown an evaporator 12 comprising a generally upright cylindrical casing 37 inside of which there is a cylinder 38 concentric with the casing 37. The upper end of the inner cylinder 38 has a reduced portion or neck 39 which opens within the upper end of the outer casing 37. The inner cylinder 38 forms within the outer casing 37 an annular space 40 within which there is located a pipe coil 41 having its turns spaced equally from the outer casing 37 and the inner cylinder 38. Around the neck 39 on the upper end of the inner cylinder 38 is located an annular tray or trough 42. Over the outer rim of the annular trough 42 there is placed an inverted U-shaped ring of capillary or wick-like material 43 which may be steel mesh. This ring of capillary material extends substantially to the bottom on the inside of the trough 42 and extends downward or hangs uniformly over the edge of the trough 42 and below the bottom thereof. The trough 42 and wick ring 43 are constructed and arranged so that the outer depending edge of the latter is horizontal and located directly above the top turn of the pipe coil 41. A conduit 57 is connected to the lower part of the inner cylinder 38 and a conduit 58 is connected to the lower end of the outer casing 37. A conduit 68 extends through the outer casing 37 and has an open end above the trough 42.

When the evaporator 12 is connected in a suitable refrigeration system, as hereinafter described, liquid refrigerant, such as ammonia, flows through the conduit 68 into the trough 42 whence it is carried by the annular capillary syphon 43 and deposited on the upper turn of the evaporator coil 41 located in the annular 55

space 40. As the liquid is deposited on the upper turn of the coil 41, it spreads out and runs to the under side of this turn. Due to the inclination of the coil turns, liquid also flows downwardly along 5 the length of the coil. Liquid also drops due to its own weight from the bottom of one turn and is interrupted by the top of the next turn. The liquid ammonia thus becomes distributed entirely over the outer surface of the evaporator 10 coil 41 as it descends in substantially a free-falling cylindrical sheet. This liquid distribution may be aided by roughening the outer surface of the coil 41 as, for instance, by electro-deposition which creates a sponge metal surface.

15 I have discovered that the degree of slope or inclination of the piping forming the coil 41 is of critical importance. Fig. 11 shows a curve obtained experimentally to determine the inclination necessary to obtain maximum covering of 20 the surface of the absorber and evaporator piping by the free-falling or random dripping liquid. This is a qualitative curve obtained by measuring heat transfer to liquid dripping on the outside of a variably inclined conduit from liquid 25 flowing therethrough. The maximum surface covering occurs when the piping has an inclination of substantially 4 degrees. A greater or less inclination results in less of the surface being covered by liquid and less heat transfer. For instance, the surface covered when the inclination is 2 degrees is substantially the same as that when the inclination is 8 degrees but less than the maximum when the inclination is about 4 degrees. I prefer an inclination of substantially 30 4 degrees and not less than 2 degrees nor more than 8 degrees.

Inert gas enters the evaporator through conduit 57 and flows upward through the inner cylinder 38, through the opening 39 into the upper end of 40 the outer casing 37, and thence downwardly in the annular space 40 and out through the conduit 58. The liquid which wets the outer surface of the coil 41 evaporates, and its vapor diffuses into the atmosphere of hydrogen which surrounds the 45 coil in the annular space 40. Due to this evaporation, the liquid and gas is cooled to a temperature corresponding to the evaporation temperature at the vapor pressure of the ammonia. This is what has been referred to as refrigeration effect. This refrigeration effect may be utilized 50 for cooling by causing a suitable fluid, such as brine, to flow through the evaporator coil 41. We may refer to the brine flowing in the coil 41 as the body to be cooled.

55 The cold refrigerant liquid and the body to be cooled, also a liquid, are in direct thermal conductive relation throughout the entire area of the wall of the evaporator coil 41, the refrigerant liquid covering the entire outside of the coil and 60 the liquid to be cooled contacting the entire inner surface of the coil. In this manner we have heat transfer from liquid to liquid through a uniformly short metallic path throughout the extent of the evaporator.

65 In an evaporator constructed in accordance with my invention, as just described, the surface wetted by liquid refrigerant is completely surrounded by inert gas. The turns of the evaporator coil 41 are equally spaced from each other 70 and equally spaced from the walls formed by the inner cylinder 38 and the outer casing 37. The smaller the spacing between the coil turns, the greater the evaporation and heat transfer surface for a given size evaporator. This spacing, however, should not be so small that liquid runs-

ning downwardly over the coil bridges the spaces between the coil turns. The spacing should be such that during operation liquid drops clear from one turn and on to the next. Likewise, the spacing of the outer surface of the coil 40 from the inner surfaces of the cylinder 38 and casing 37 should be as small as possible without incurring bridging of liquid between the coil and the walls. The reason for this is that bridging of liquid creates localized flow of the descending liquid, interfering with the desired cascading thereof which completely covers the outer surface of the coil. I have found that a distance of less than $\frac{1}{8}$ inch between coil turns and between the coil and evaporator walls is liable to incur bridging of liquid. 10 I therefore prefer a spacing between coil turns and between the coil and the inner surfaces of the annular space 40 of not less than $\frac{1}{8}$ inch but as near this dimension as practicable, that is, on the order of three sixteenths of an inch. 15 20

Referring to Fig. 2 of the drawings, there is illustrated more or less diagrammatically a refrigeration system including a generator 10, a condenser 11, the above described evaporator 12, and an absorber 13. The generator 10 and the absorber 13 are connected for circulation of liquid therebetween by members including a liquid heat exchanger 14. The evaporator 12 and the absorber 13 are interconnected for circulation of gas therebetween by members including a gas 25 heat exchanger 15. The generator 10 is connected to the condenser 11 for flow of vapor from the generator to the condenser, and the condenser 11 is connected to the evaporator 12 for flow of liquid from the condenser to the evaporator by 30 members hereinafter described.

The generator 10 comprises a casing 16 in the form of an upright cylinder. A plurality of flues or fire tubes 17 extend vertically through the casing 16. At the bottom of the casing 16 is a heating or combustion chamber 18, and the lower ends of the fire tubes 17 open in the upper part of this chamber. A flue, not shown in this figure, may be provided for conducting flue gases from the upper ends of the tubes 17. A suitable heater such as a gas burner 19 is located beneath the combustion chamber 18 so that the burner flame is projected into this chamber and thence into the tubes 17. The tubes 17 provide a desired surface for transferring heat to liquid surrounding 40 these tubes in the casing 16. 45

A pipe coil 20 is located in the chamber 18 above the burner 19 so as to be heated directly by the burner flame. The lower end of the coil 20 is connected to the lower end of an upright conduit 21. The upper end of the conduit 21 is connected to the lower part of the generator casing 16. The upper end of the coil 20 is connected by a rising conduit 22 to the upper part of a gas and liquid separating vessel 23. The upper end of the generator casing 16 is also connected to the upper part of the vessel 23 by a conduit 24. The internal diameter of the conduit forming the coil 20 and the rising conduit 22 is advantageously 50 sufficiently small that gas and liquid cannot pass each other therein so that gas formed by vaporization of liquid in the coil 20 will be trapped as bubbles in liquid, thereby adding a piston effect to the resulting decrease in weight of a fluid column in the coil 20 and conduit 22 compared to an equal column of liquid to effect upward flow of liquid in the coil 20 and conduit 22 into the vessel 23. Although only one coil 20 and rising conduit 22 are illustrated in this figure, it will be un- 55 60 65 70 75

derstood that a plurality of such coils and rising conduits may be provided.

The upper part of the generator casing 16 is connected to the lower end of a slightly tilted but generally horizontal conduit 25, which will be herein referred to as an analyzer. The analyzer 25 is provided with a plurality of baffles or partitions 26 each provided with an opening 27 in the upper part thereof and an opening 28 in the lower part thereof. These openings may best be seen in Fig. 3. The upper opening 27 is in the form of a horizontal slot having serrations in the upper edge thereof. The lower opening 28 may be a circular hole. The upper end of the analyzer 25 is connected to the lower part of a vessel 29 which may be considered as part of the analyzer.

The upper part of the analyzer vessel 29 is connected by means of a conduit 30 to the lower end of a rectifier 31. The rectifier 31 comprises an upright tube 32 surrounded by a jacket 33. The lower end of the tube 32 projects through the bottom of the jacket 33, and the upper end of the tube 32 is open in the upper part of the jacket 33. The interior of the tube 32 may be provided with suitable fins or baffles 34. The upper end of the rectifier jacket 33 is connected to the upper end of the condenser 11. The lower end of the condenser 11 is connected by means of a conduit 35 to the right hand leg of a U-shaped conduit 36. The right hand leg of the conduit 36 extends appreciably above the lower end of the condenser 11, and the left-hand leg of the conduit 36 is very short and connected to the rectifier jacket 33 at a point appreciably below the lower end of the condenser 11.

The evaporator 12 has been described in connection with Fig. 1 and the parts are indicated by the same reference numerals as in Fig. 1.

The absorber 13 is constructed somewhat similarly to the evaporator 12. It comprises an upright cylindrical casing 44 and an inner cylinder 45 concentric therewith and forming therebetween an annular space 46. Within the annular space 46 is located a pipe coil 47 with its turns spaced equidistant from the outer casing 44 and the inner cylinder 45. The upper and lower ends of the inner cylinder 45 are closed, except that the lower end is provided with an opening 48 and the upper end is connected by means of a conduit 49 to the upper end of the right hand leg of the U-shaped conduit 36 previously described. On the upper end of the inner cylinder 45 is located an annular trough 50. Over the outer rim of the trough 50 is located a ring of capillary material 51 of inverted U-shape, the inner edge extending substantially to the bottom of the tray or trough 50, and the outer edge being horizontal and depending uniformly below the bottom of the trough and located directly over the upper turn of the pipe coil 47. This structure is best shown in the enlarged detail view of Fig. 4.

The gas heat exchanger 15 comprises a generally horizontal cylindrical casing 52 containing a plurality of horizontal tubes 53. The tubes 53 connect end chambers 54 and 55 formed by partitions in the casing 52. The end chambers 54 and 55 connected by the tubes 53 form one passage of the gas heat exchanger, and the space around the tubes 53 forms the other passage of the heat exchanger. The upper part of the absorber 13 is connected by a conduit 56 to one end chamber 54 of the gas heat exchanger, and the other end chamber 55 is connected by a conduit 57 to the lower end of the inner cylinder 33.

of the evaporator 12. The lower part of the outer casing 37 of the evaporator 12 is connected by a conduit 58 to one end of the space around the tubes 53, and the other end of this space is connected by a conduit 59 to the lower part of the absorber 13.

Referring now to the connections for circulation of liquid between the generator 10 and the absorber 13, the lower part of the gas and liquid separating vessel 23 is connected to the upper part of the absorber 13 by a conduit 60, the inner passage of the liquid heat exchanger 14, and a conduit 61. The upper end of the conduit 61 depends above the absorber tray 50. The lower part of the absorber 13 is connected to the analyzer vessel 29 by a conduit 62, the outer passage of the liquid heat exchanger 14, and a conduit 63.

Adjacent the top of the evaporator 12 is a looped conduit 64, which may be referred to as a high temperature evaporator or precooler. The upper part of the ends of this evaporative precooler are connected by conduits 65 and 66 respectively to the chamber in the gas heat exchanger 15 which surrounds the tubes 53. A conduit 67 is connected from the bottom of the U-shaped tube 36 to one end of the conduit 64, and one end of a conduit 68 is connected to the other end of the conduit 64. The other end of conduit 68 extends into the evaporator 12 and depends above the evaporator trough 42.

The upper end of the evaporator coil 41 is connected to the upper end of a cooling coil 69 in a chamber to be cooled 70. The lower end of the cooling coil 69 is connected to a suitable pump 71 or other liquid displacing means which in turn is connected to the lower end of the evaporator coil 41.

The upper end of the absorber coil 47 is connected by a conduit 72 to a condenser cooling coil 73. The other end of the condenser cooling coil 73 is connected to a conduit 74 which extends in thermal contact with a portion 75 of conduit 30, which will herein be referred to as a first rectifier or high temperature rectifier. The lower end of the absorber coil 47 is adapted to be connected to a source of cooling water by means of a conduit 76, and conduit 74, beyond the high temperature rectifier section 75, is adapted to be connected to a suitable drain.

The system which has just been described with respect to its constituent parts and connections thereof, is charged by inserting through a suitable charging plug, not shown, a quantity of water solution of ammonia, and hydrogen at a pressure such that the total pressure in the system during operation will be sufficiently high for condensation of ammonia at that total pressure and a certain condenser temperature which may be a fairly high cooling water temperature, or room temperature should the condenser be air-cooled. The liquid assumes the lowest possible level in the system, and the space above the liquid is filled with gas. When the burner 19 is lighted, heat from the burner is transmitted directly to the coil 20, and by means of the fire tubes 17 to the liquid in the generator casing 16. Heating of liquid in the coil 20, causes expulsion of ammonia vapor out of solution. The expelled vapor creates in the coil 20 and the rising conduit 22 a fluid column lighter than an equivalent column of liquid only, so that the combination vapor and liquid column rises in conduit 22 into the gas and liquid separating vessel 23. From the vessel 23, the gas flows in conduit 24 to the

upper part of the generator casing 16. Heating of liquid in the generator casing 16 also causes expulsion of ammonia vapor out of solution when the boiling point of the solution is reached. This vapor rises into the upper part of the generator casing 16. The vapor which accumulates in the upper part of the generator casing 16 escapes therefrom by bubbling through liquid in the analyzer conduit 25 and the analyzer vessel 29. The baffle plates 26 in the analyzer conduit 25 prevent the vapor from merely flowing along under the top of the conduit 25, and cause the vapor to pass downwardly and through the slots 27 in the discs 26. The serrations in the upper edge of the slots 27 break up the vapor flow so as to create a more extensive contact of the vapor with the liquid as they flow in countercurrent relationship through the analyzer conduit 25. Liquid from the separation vessel 23 flows through conduit 60, the inner passage of the liquid heat exchanger 14, and conduit 61 into the upper part of the absorber 13. During operation of the system, ammonia vapor is expelled from solution in the generator casing at a first temperature, and more ammonia vapor is expelled from solution in the coil 20 at a higher temperature, so that liquid which enters the absorber 13, as just described may be referred to as weak absorption liquid, this phraseology having reference to the relatively low concentration of ammonia. In the absorber 13, the weak absorption liquid becomes enriched by absorption of ammonia vapor, as hereinafter described, and the enriched absorption liquid flows from the lower part of the absorber through conduit 62, the outer passage of the liquid heat exchanger 14, and conduit 63 into the analyzer vessel 29 and the analyzer conduit 25 back to the generator 10. The lower openings 28 in the analyzer baffles 26 permit the flow of liquid in the analyzer 25 countercurrent to the previously described flow of vapor therethrough. The ammonia vapor passes out of contact with liquid in the analyzer vessel 29 at a place where the liquid has a high concentration of ammonia. The purpose of this is to decrease the amount of water vapor leaving the generator.

Vapor flows from the upper part of the analyzer vessel 29 through conduit 30, the high temperature rectifier 75, and the liquid cooled rectifier 31 into the upper end of the condenser 11. Water vapor condensed in the rectifiers flows back through conduit 30 to the liquid circuit. In the condenser 11, ammonia vapor, substantially at the total pressure in the system, is condensed to liquid by heat transfer to water flowing through the condenser cooling coil 73. The liquid ammonia flows from the lower end of the condenser 11 through conduit 35 into the U-shaped conduit 36 and the rectifier jacket 33. It will now be understood that the liquid in the rectifier jacket 33 causes cooling of the rectifier 31. Cooling water from the condenser cooling coil 73 flows through conduit 74 in heat exchange relation with the conduit 30 at 75 and causes cooling of this higher temperature rectifier.

Liquid ammonia flows from the lower part of the U-shaped conduit 36 through conduit 67 into one end of the evaporative precooler formed by the looped tube 64. The liquid flows along the lower part of the tube 64 to the other end thereof whence it flows through conduit 68 into the upper part of the evaporator.

During operation of the system, the inert hydrogen gas is substantially confined to the circuit

including the evaporator 12 and the absorber 13 which are interconnected as previously described by the gas heat exchanger 15.

In the evaporator 12 the ammonia evaporates in the presence of hydrogen, as set forth in connection with Fig. 1, and the cooling brine or other heat conducting liquid flows through the evaporator coil 41 and thence through the cooling coil 69 in heat transfer relation with air in the enclosure 70. Liquid may be circulated between the cooling coil 69 and the evaporator coil 41 by means of the pump 71. In the evaporator coil 41, the brine is cooled by heat transfer to the liquid ammonia on the outer surface of this coil. In the cooling coil 69, the brine is warmed by heat transfer thereto from air in the enclosure 70. The pump 71 is connected and arranged to cause circulation of the brine so that it flows upwardly through the evaporator coil 41. The reason for this will be hereinafter explained.

In order that evaporation of liquid ammonia may continue in the evaporator 12 at the desired temperature or temperatures, it is necessary to remove ammonia vapor from the atmosphere around the evaporator coil 41 so that the partial pressure of ammonia will be maintained at the desired value. To this end, the mixture of gas and vapor, herein referred to as rich gas, is removed from the evaporator and replaced by what is herein termed weak gas, that is, gas containing a relatively small quantity of ammonia vapor.

The strong gas from the evaporator 12 is conducted through conduit 58, the gas heat exchanger 15, and conduit 59 into the lower part of the absorber 13. Weak absorption liquid emerging from the upper end of conduit 61 in the absorber 13 is deposited in the absorber distributing tray or trough 50 from which it is transferred by the annular capillary siphon 51 onto the upper turn of the absorber coil 47 in the annular space 46. The liquid flows downwardly over the absorber coil 47 in the same manner as the liquid ammonia flows downwardly over the evaporator coil 41, as previously described. Ammonia vapor diffuses out of the atmosphere in the annular chamber 46 of the absorber and enters into solution at the surface of the liquid wetting the absorber coil 47. This absorption of ammonia is accompanied by liberation of heat which is transferred from the absorption liquid to cooling water which flows in the absorber coil 47. Weak gas from the absorber is conducted through conduit 56, the gas heat exchanger 15, conduit 57, and the inner cylinder 38 of the evaporator 12 to the upper part of the evaporator.

The manner in which the gas circulation occurs is as follows: The specific density of ammonia vapor is greater than that of hydrogen, so that the column of gas formed by diffusion of ammonia vapor into the atmosphere of the evaporator 12 is heavier than the column of gas formed when ammonia vapor is removed from the atmosphere in the absorber 13. The resulting unbalance between these two columns of gas creates circulation thereof, upward in the absorber 13, and downward in the evaporator 12. In the gas heat exchanger 15, heat is transferred from the weak gas flowing in the tubes 53 to the strong gas flowing in the chamber around these tubes.

Referring now to the looped tube 64, the ends of this tube are connected by conduits 65 and 66 respectively to the chamber around the tubes 53 of the gas heat exchanger 15. There is, there-

fore, an atmosphere in the tube 64, above the surface of liquid flowing along the bottom thereof, containing ammonia vapor at the same partial pressure as at the bottom of the evaporator 12. The vapor pressure of the warm liquid entering the conduit 64 from the condenser being greater than the partial pressure of the vapor in the atmosphere in this tube, the tendency to equalize results in evaporation of liquid and 10 cooling thereof before entrance into the evaporator 12. The formation of vapor in the evaporative precooler 64 results in flow of gas in the path formed by conduit 65, the tube 64, and conduit 66 due to the difference in weights of the 15 columns of gas in this path.

Referring now to the vessel 45 within the absorber 13, the upper end of this vessel is connected by conduit 49 to the upper end of the right hand leg of the U-shaped conduit 36, and 20 the lower end of the vessel 45 communicates with the interior of the absorber through the opening 48. During normal operation of the system, the vessel 45 contains gas having a concentration of 25 ammonia vapor substantially like that in the lower part of the absorber. The conduit 49 normally provides a passage for non-condensable gas which may issue from the lower end of the condenser 11 through conduit 35, the right hand leg of the trap 36, and conduit 49 back to the gas 30 circuit. If the temperature of the cooling water in the condenser cooling coil 73 should be abnormally high so that the condenser temperature is too high for condensation of ammonia at the existing pressure in the system, uncondensed ammonia vapor will flow through conduit 49 into the vessel 45, displacing gas from this vessel through the opening 48 into the absorber 13 which is in the active gas circuit. In this manner, 35 a rise in pressure in the system takes place so that condensation of ammonia may continue at the higher temperature. The vessel 45 is herein referred to as a pressure vessel. During periods when the cooling water temperature is high, the pressure vessel 45 acts as a continuation of the 40 condenser, and ammonia vapor condensed herein returns to the liquid circuit through the opening 48 in the bottom.

Let us return now to the structures of the evaporator 12 and the absorber 13 in Figs. 1 and 50 2, these structures being essentially the same as far as gas and liquid contact is concerned. Referring more particularly to the evaporator 12, we have previously described the location of the helical pipe coil 41 as being in an annular space 55 40 between the inner and outer walls of the evaporator. This of course is true, but this location of the coil 41 further divides the annular space 40 into two annular spaces, one on the inside of the coil 41 and the other on the outside of the 60 coil 41. The liquid refrigerant, ammonia, is dripping or cascading downward over the coil 41 so that the inert gas, hydrogen, flows in two annular paths with respect to the liquid ammonia. The ammonia evaporates at the surface of the 65 liquid on the coil 41 and the resulting ammonia vapor diffuses throughout the annular space 40 in the presence of the hydrogen. If the gas were not allowed to flow through the evaporator, the ammonia vapor would, given sufficient time, 70 diffuse equally throughout the evaporator space and reach equilibrium at the saturation temperature and pressure of the ammonia. However, this state of equilibrium is not reached during operation because, due to circulation of gas as 75 previously described, the rich gas is continually

replaced in the evaporator by weak gas. Whether the gas is flowing or standing still, there is a maximum distance through which ammonia vapor has to move from where it is formed at the liquid surface in tending to establish equilibrium. Since the coil 41 is located centrally of the annular space 40, the maximum diffusion distance from the coil into the space 40 is less than the width of the space 40. Since all the diffusion distances, that is, the distances in directions normal to the liquid surface, are not all exactly the same, we may better refer to the mean diffusion distance. It has been found that the capacity or quantity of liquid evaporated per unit of time is increased upon decrease in the mean diffusion 15 distance. This is the reason that, as previously set forth, the spacing between the coil 41 and the walls of the evaporator is made as small as possible. In the present embodiment, bridging of liquid is a limiting factor of this spacing. I 20 wish to point out, however, that I may replace the coil 41 by a cylinder of, for instance, capillary material, and obtain a very small gas space normal to the liquid surface. Also, I may distribute the liquid over both the inner and outer wall 25 surfaces of the space 40 rather than over a member in the center of the space 40 and still have a diffusion distance less than the width of the space 40. In this case the gas would still 30 flow in two annular paths with respect to the liquid ammonia, the two annular paths being in effect one larger annular path with liquid surface on both sides thereof. I have used the helical coil, however, because it affords a large 35 liquid surface in a small evaporator, provides for better heat transfer from the liquid ammonia to the liquid to be cooled which flows in the coil, and effects a novel and efficient gas flow as will hereinafter appear.

The diffusion distance cannot be made zero 40 because this would mean that there would be no gas and therefore no evaporation of ammonia at a temperature lower than the condenser temperature and no refrigeration would be produced. Neither should the decrease in diffusion distance 45 interfere with the necessary rate of gas circulation because the decrease in capacity occasioned by decrease in gas flow would nullify any increase in capacity due to decrease in diffusion distance.

In the subject type of system the gas circulation 50 is produced by difference in specific density of the weak and rich gas. The density of the rich gas is determined by the average concentration of ammonia vapor in the gas which leaves the evaporator 12 through conduit 58, referring to Fig. 2. The density of the weak gas is determined by the average concentration of ammonia vapor in the gas leaving the absorber 13, through conduit 56. Throughout the evaporator 55 and the absorber there is a gradient density between that of the rich and weak gas. As previously explained, it is the inherent force within the system due to the difference in specific densities of the rich and weak gas columns which causes the gas circulation. Part of this force 60 causes actual movement of gas and another part of this force is expended in overcoming resistance in the gas circuit comprising the evaporator, the absorber, the gas heat exchanger, and the interconnecting conduits previously described. I have 65 therefore provided in the evaporator and the absorber a path of gas flow having a very small diffusion distance but a large cross sectional area. In the evaporator this is the cross sectional area 70 75

of the annular space between the coil 41 and the inner wall 38 plus the cross sectional area of the annular space between the coil 41 and the outer wall 37. I may make the evaporator 12 as large or as small as desired and by keeping the same width annular space 40 the diffusion distance in the large evaporator will be no more than in the small evaporator although the cross sectional area in the path of gas flow will be greater to accommodate more gas in the larger evaporator.

From the above it will be understood that other things, such as liquid surface and heat transfer, being constant, the capacity varies with the rate of gas flow and inversely with the mean diffusion distance. Under constant conditions evaporation of liquid into a moving stream of gas is proportional to the square root of the velocity. However, in the refrigeration system we have to take into consideration that gas flowing between the high temperature absorber and the low temperature evaporator incurs a heat loss which is cut down only within the efficiency of the heat exchanger. Other things being constant, then, the maximum efficiency would be obtained when the gas flowing from the evaporator to the absorber contains saturated ammonia vapor. This is not obtained on account of the concentration gradient of ammonia vapor from the surface of the liquid ammonia in the direction of the diffusion distance into the gas stream. With a smaller mean diffusion distance, a desired average concentration of gas leaving the evaporator is reached in a shorter length of time, that is, a unit quantity of gas passes through the evaporator in a shorter length of time and the velocity of gas flow through the evaporator is thus increased resulting in an increase in capacity without sacrificing efficiency.

As the gas flows through the evaporator 12, and the same thing happens in the absorber 13, it passes alternately into annular streams on each side of the coil 41 and then in a single large annular stream between the turns of the coil. The cross sectional area of each of the two separated streams being much less than the cross sectional area of the intermediate large stream, the resulting alternations in energy of flow produce turbulence. This turbulence in the gas stream results in convection of ammonia vapor from the surface of the liquid ammonia into the gas stream. This aids the natural diffusion of ammonia and results in an increase of efficiency and also greater capacity because a desired average concentration of ammonia in the gas is reached in a shorter length of time. In the absorber the convection caused by turbulence abets natural diffusion of ammonia vapor out of the gas stream to the surface of the absorption liquid. Herein I have used the word "diffusion" in a technical sense of either dispersion or concentration of one vapor or gas in a space occupied by another gas. With respect to the evaporator we say that the ammonia vapor diffuses into the hydrogen and with respect to the absorber we say that the ammonia vapor diffuses out of the hydrogen.

In Fig. 5 is shown a system like that previously described in connection with Fig. 2 and like parts in these two figures are indicated by the same reference numerals. Whereas in the system illustrated in Fig. 2 the absorber 13 and the condenser 11 are cooled by a supply of water which goes to waste, I may provide an evaporative cooling circuit or spray tower for the absorber 13 and condenser 11' as illustrated in Fig.

5. The condenser 11' is located in a housing 71 having a water tank 78 in the lower part thereof. Air enters the casing 77 through an opening 79 below the condenser 11' and is discharged by a fan or blower 80 above the condenser, thus causing a flow of air over the condenser coil 11'. Water is admitted to the tank 78 through a conduit 81 regulated by a float controlled valve 82. The tank 78 is connected by a conduit 83 to the lower end of the absorber coil 41. The upper end of the absorber coil is connected by a conduit 84 to a pump 85 which is in turn connected by a conduit 86 to a spray nozzle 87 above the condenser coil 11'. Cooling water from the tank 78 flows through conduit 83 into the absorber coil 41 and is then raised by the pump 85 through conduits 84 and 86 to the spray nozzle 87 from which the water is showered onto the condenser coil 11'. Due to the upward flow of air through the casing 77, the water sprayed downwardly therein is cooled toward its wet bulb temperature. Water lost by evaporation into the air stream is replaced from conduit 81 under the control of the float operated valve 82.

The upper end of the evaporator coil 41 is connected by a conduit 88 to a spray nozzle 89 in a casing 90. A water tank 91 in the lower part of the casing 90 is connected by a conduit 92, a liquid pump 93, and a conduit 94 to the lower end of the evaporator coil 41. The tank 91 may be suitably connected to a source of water and the inlet to the tank controlled by a float operated valve to permit inlet of make-up water. The pump 93 raises water from the tank 91 through the evaporator coil 41 to the spray nozzle 89 which showers the water down through the casing 90 back to the tank 91. Air from a room 95 to be cooled is circulated by a fan or blower 96 through a conduit 97 and a conduit 98 to the lower part of the spray tower 90, and thence upwardly through the spray tower to a conduit 99 through which the air is returned to the room 95. Fresh air may be admitted through a conduit 100. The air in passing upwardly through the spray tower 90 is cooled by the cold water from the nozzle 89. Suitable baffle plates 101 may be provided to disentrain free water from the stream of air before it is returned to the room 95.

In both of the arrangements illustrated in Figs. 2 and 5, water or brine is circulated upwardly through the evaporator coil 41. The gas flows downwardly in the annular passage 40 in which the coil 41 is located. Since the partial pressure of ammonia in the gas increases in the direction of the gas flow, the region of lowest partial pressure and, therefore, the lowest evaporator temperature is in the upper part of the evaporator adjacent to where the weak gas enters. Thus, the water flowing upwardly through the evaporator coil 41 is progressively cooled and leaves the evaporator substantially at the place of lowest temperature, thereby utilizing the full cooling effect of the evaporator.

In the systems illustrated in Figs. 2 and 5, the absorber 13 is provided with the desired annular gas passage by locating therein the cylindrical pressure vessel 45, thereby effecting the desired absorber structure and at the same time eliminating the requirement of additional space for a pressure vessel. The evaporator precooler 64 may also be utilized for producing refrigeration at a higher temperature than that of the evaporator 12, thereby obtaining still further useful refrigeration from the system. The burner 18 may be controlled in any desired manner.

For instance, it may be thermostatically regulated responsive to temperature of the evaporator 212.

In Figs. 6 to 10 is shown a refrigeration apparatus unit embodying my invention. The parts of this apparatus are substantially as described in connection with the system shown diagrammatically in Fig. 2, and are connected in the same manner. The apparatus is mounted in a rectangular frame 209 composed of angle irons. The generator 210 is located substantially centrally in the lower part of the frame. The liquid heat exchanger 214 is formed by a concentric tube coil which encircles the generator casing 216. A flue 208 is provided for conducting spent gases from the upper ends of the flues or fire tubes 217 which extend upwardly through the generator from the heating chamber 218. Two coils 220 are located in the heating chamber 218 and have their lower ends connected to the lower end of the upright conduit 221, the upper end of which is connected to the lower part of the generator casing 216. The upper ends of the coils 220 are connected by means of rising conduits 222 to the gas and liquid separating vessel 223. The upper part of the vessel 223 is connected to the generator by means of a conduit 224, and the lower part of the vessel 223 is connected to the liquid heat exchanger 214 by conduit 260. The analyzer 225 and analyzer vessel 229 are like that described in connection with Fig. 2. The generator 210, the liquid heat exchanger 214, the separating vessel 223 and its connections, and the analyzer 225 are enclosed by suitable thermal insulating material 207, such as mineral wool which is retained in place by a light sheet metal casing 206. Any suitable heater, not shown, may be arranged directly beneath the coils 220 in the heating chamber 218.

The evaporator 212 and the absorber 213 are located at opposite ends of the frame 209, the absorber 213 being at a level above that of the generator 210, and the evaporator 212 being somewhat higher than the absorber 213. Members interconnecting the absorber and the evaporator 45 include a gas heat exchanger 215 similar to that described in connection with Fig. 2. The evaporative precooler coil 264 is located directly above the upper end of the evaporator 212, and this precooler, the evaporator, and adjacent portion 50 of the gas heat exchanger 215 are encased by suitable thermal insulation material 205.

The condenser 211 comprises a concentric tube coil located adjacent the top of the frame 209 and encircling the leg of the rectifier U-tube 236 which is connected by the vent conduit 249 to the pressure vessel 245 within the absorber 213. The lower part of the U-tube 236 is connected by the conduit 267 to the evaporative precooler 264 which in turn is connected by conduit 268 to the evaporator 212. The evaporator precooler 264 is connected to the gas heat exchanger 215 by conduits 265 and 266.

The absorber 213, the condenser 211, and the high temperature rectifier 215 are cooled by water 65 which flows from conduit 276 upward through the absorber coil 247, then through conduit 272 to the condenser cooling coil, and thence through conduit 274 which extends in thermal contact with the vapor conduit 230 at 275.

The insulation material around the generator and around the evaporator is shown only in Figs. 6, 70 so as not to obstruct view of the several connecting conduits in the other figures. In Fig. 7 may be seen conduits 269 and 269a which are 75 connected to the lower and upper ends of the

evaporator coil respectively and to which connection may be made for flow of fluid to be cooled through the evaporator.

This apparatus unit may be supplied with about twenty-eight per cent solution of ammonia in water, and hydrogen under a desired pressure as explained in connection with Fig. 2. Heat from any suitable source, such as a gas burner, is applied to the coils 220 and the generator 210, whereby ammonia vapor is expelled from solution at a first temperature in the generator, and at a higher temperature in the coils 220. This brief reference to operation of the system may best be followed by reference to Fig. 6. Vapor expelled from solution in the coils 220 causes 10 upward flow of vapor and liquid in the rising conduits 222 into the separating vessel 223 in the manner previously described. Vapor flows from the vessel 223 through conduit 224 into the upper part of the generator casing 216, from where all the vapor bubbles through liquid in the analyzer 225 and passes into the analyzer vessel 229. From the vessel 223, liquid flows through conduit 260, the liquid heat exchanger 214 and conduit 261 into the upper part of the absorber 213. Enriched liquid flows from the lower part of the absorber 213 through conduit 262, the liquid heat exchanger 214, and conduit 263 into the analyzer vessel 229 from where it flows to the analyzer conduit 225 into the generator. 20

Vapor flows from the upper part of the analyzer vessel 229 through conduit 230 to the liquid cooled rectifier 231. Water vapor condensed in the high temperature rectifier 275 and in the liquid cooled rectifier 231 flows back to the liquid circuit through conduit 230. Ammonia vapor (here see Fig. 7) flows from the low temperature rectifier 231 into the upper end of the condenser coil 211. In the latter, the ammonia vapor, substantially at the total pressure in the system, is condensed to liquid which flows through conduit 235 into the rectifier U-tube 236. From the lower part of the U-tube 236, liquid ammonia flows through conduit 267, the evaporative precooler 264, and conduit 268 into the evaporator 212. In the evaporator, the liquid flows downwardly over the evaporator coil 241, in a manner previously described, and evaporates, producing a refrigerating effect to cool fluid in the coil 241. The vapor diffuses into the atmosphere of inert gas, hydrogen. Rich gas flows from the evaporator 212 through conduit 258, the gas heat exchanger 215, and conduit 259 into the absorber. In the latter, ammonia vapor diffuses out of the gas and is absorbed into weakened solution flowing 55 downwardly over the absorber coil 247. The weak gas returns from the absorber to the evaporator through conduit 256, gas heat exchanger 215, and conduit 257. Rich gas from the gas heat exchanger 215 flows through conduit 265, 60 and conduit 266 into the evaporative precooler 264, and conduit 266. 65

Although I have described and explained my invention as embodied in a particular type of system in which gas circulation is automatically produced by a force within the system, it will be understood that it may be practiced in any system which makes use of evaporation of refrigerant in the presence of inert gas, whether gas circulation is produced by a fan, blower, injector, turbine, or other gas impelling means. It will also be understood that there may be variations in structure as, for instance, the use of banks of tubes or pipes instead of the helical coils in the evaporator and absorber, or both. My in- 70 75

vention, therefore, is not limited except as indicated by the following claims.

What I claim is:

1. Refrigeration apparatus of the absorption type employing an inert gas including structure for effecting gas and liquid contact comprising piping having sections thereof arranged one above the other, and means for delivering liquid upon said piping so that the liquid descends by gravity from one section to another and over the exterior surface of said piping, said piping having a slope of substantially four degrees to effect substantially maximum wetting of the exterior surface thereof by the descending liquid. 5
2. Refrigeration apparatus of the absorption type employing an inert gas including structure for effecting gas and liquid contact comprising piping having sections thereof arranged one above the other, and means for delivering liquid upon said piping so that the liquid descends by gravity from one section to another and over the exterior surface of said piping, said piping having a slope lying in a range between and including two and eight degrees. 10
3. Absorption type refrigeration apparatus employing an inert gas including a generator, a condenser, an evaporator, an absorber, a pressure vessel located within said absorber and communicating therewith, and a conduit connected from the outlet end of said condenser to said pressure vessel. 15
4. Absorption refrigeration apparatus employing an inert gas including a generator, a condenser, an evaporator, an absorber, said absorber having inner and outer walls forming therebetween a substantially annular space for flow of inert gas, said inner wall enclosing a storage chamber for inert gas, a connection from said chamber into the absorber space, and a conduit connected from the outlet end of said condenser to said chamber. 20
5. In an absorption refrigerator, a generator, a condenser, an evaporator, an absorber, and members connecting said parts to form a system for flow of refrigerant, absorption liquid, and inert gas, said absorber including a cylindrical member constituting a pressure vessel, an outer shell concentric with said vessel, means to provide a cascade of absorption liquid midway between said vessel and said outer shell, a connection between said vessel and a point in the system between the generator and the evaporator, and said vessel being connected to the absorber space outside the same. 25
6. In a refrigerating apparatus of the kind in which refrigerant evaporates into inert gas, an evaporator including spaced vertical walls, vertically spaced pipe portions between said walls equidistantly spaced therefrom, said pipe portions being disposed for dripping of liquid from one to another along their length and being spaced vertically to prevent bridging of liquid, said pipe portions being so close to said vertical walls as to provide minimum diffusion distance, without bridging of liquid, means to cause flow of gas between said walls, means to supply liquid refrigerant to flow over said pipe portions, and means to circulate fluid to be cooled through said pipe portions. 30
7. In a refrigeration system of the kind in which refrigerant liquid evaporates and diffuses into an inert gas, the improvement which consists in alternately flowing the liquid refrigerant in free falling condition and in heat exchange relation with a medium to be cooled, and flowing inert gas on each side of the free falling liquid refrigerant in direct contact therewith in paths of like characteristics and of a width on the order of three sixteenths of an inch. 35
8. A refrigeration system including structure forming an annular place of evaporation, a member for conducting liquid refrigerant fluid to said place of evaporation, members for conducting inert gas to and from said place of evaporation, and a pipe coil arranged concentrically in said annular place and constructed and arranged to form a downward path of flow for liquid refrigerant fluid on its exterior surface and interiorly conduct a fluid to be cooled, the width of said annular place being such that with said pipe coil therein, there is a minimum diffusion distance for refrigerant in inert gas without bridging of liquid. 40
9. A refrigeration system including an evaporator formed by two concentric upright cylindrical members providing an annular space therebetween, a pipe coil located in said annular space substantially equidistant from both said members, a member for conducting liquid refrigerant fluid to the upper part of said annular space, means for conducting inert gas through the inner upright cylindrical member and to one end of said annular space, and means for conducting inert gas from the opposite end of said annular space, said pipe coil being constructed and arranged to interiorly conduct fluid to be cooled, a receptacle for liquid conducted to the upper part of said annular space, and a capillary siphon for distributing liquid from said receptacle onto an upper turn of said pipe coil. 45
10. In a refrigeration system of the kind in which refrigerant liquid evaporates and diffuses into an inert gas, the improvement which consists in dripping liquid refrigerant in a sheet-like path in free falling condition, obstructing the free fall of liquid in said path, flowing inert gas on each side of said sheet-like path in direct contact with the liquid refrigerant in paths of like characteristic and of a width on the order of three sixteenths of an inch, and transferring heat from an object to be cooled to the obstructing medium. 50
11. In a refrigeration system of the kind in which refrigerant liquid evaporates and diffuses into an inert gas, the improvement which consists in flowing liquid refrigerant in free falling condition in a sheet-like path of annular form, flowing a medium to be cooled through said path in indirect heat transfer relation with the liquid refrigerant and thereby obstructing the free fall of liquid refrigerant, and flowing inert gas in narrow unobstructed paths of like characteristics, including width and variations of width, on each side of the sheet-like path in direct contact with the liquid refrigerant, the width of the inert gas path being such as to provide a minimum diffusion distance without bridging of liquid. 55
12. In a refrigeration system of the kind in which refrigerant liquid evaporates and diffuses into an inert gas, the improvement which consists in flowing liquid refrigerant in free falling condition in a sheet-like path of annular form, flowing a medium to be cooled through said path in indirect heat transfer relation with the liquid refrigerant and thereby obstructing the free fall of liquid refrigerant, flowing inert gas in narrow unobstructed paths downward on each side of the sheet-like path in direct contact with the liquid refrigerant, and conducting inert gas prior to contact with the liquid refrigerant in indirect heat exchange relation with the inert gas in one 60
- 75

of said paths, the width of the inert gas path being such as to provide a minimum diffusion distance without bridging of liquid.

13. In a refrigerating apparatus, an absorber including spaced vertical walls, vertically spaced pipe portions between said walls equidistantly spaced therefrom, said pipe portions being disposed for dripping of liquid from one to another along their length and being spaced vertically to prevent bridging of liquid, said pipe portions being close to said vertical walls but spaced to prevent bridging of liquid, means to cause flow of gas between said walls, means to supply weak absorption liquid to flow over said pipe portions, and means to circulate cooling fluid through said pipe portions.

14. An absorption refrigeration system including structure forming a substantially annular place of absorption, a member for conducting absorption liquid to said place of absorption, members for conducting gas to and from said place of absorption, and a pipe coil arranged substantially concentrically in said annular place and constructed and arranged to form a downward path of flow for absorption liquid on its exterior surface and interiorly conduct a cooling fluid.

15. An absorption refrigeration system including an absorber formed by two upright cylindrical members providing an annular space therebetween, a pipe coil located in said annular space substantially equidistant from both said members, a member for conducting absorption liquid to the upper part of said annular space, members for conducting gas to and from opposite ends of said annular space, said pipe coil being constructed and arranged to interiorly conduct cooling fluid, a receptacle in the upper part of said annular space and to which liquid is conducted, and a capillary siphon for distributing liquid from said receptacle onto an upper turn of said pipe coil.

16. In a refrigeration system of the kind in which refrigerant liquid evaporates and diffuses into an inert gas and is thereafter absorbed, the improvement which consists in alternately flowing absorption liquid in free falling condition and in heat exchange relation with a cooling medium, and flowing a mixture of refrigerant vapor and inert gas on each side of the descending liquid in direct contact therewith in paths of like characteristic and of a width on the order of three sixteenths of an inch.

17. In a refrigeration system of the kind in which refrigerant liquid evaporates and diffuses into an inert gas and is thereafter absorbed, the improvement which consists in flowing absorption liquid in a sheet-like path in free falling condition, obstructing the free fall of liquid in said path, flowing a mixture of refrigerant vapor and inert gas on each side of said sheet-like path in direct contact with the absorption liquid in paths of like characteristic and of a width on the order of three sixteenths of an inch, and cooling the obstructing medium.

18. A cooling element including wall structure forming a horizontally narrow, vertically elongated space, a plurality of conduit sections located one above another centrally in said space and adapted to interiorly conduct a fluid to be cooled, means for delivering refrigerant liquid upon the exterior of said conduit sections, and members for conducting gas to and from said space, the horizontal width of said space being such as to provide a minimum diffusion distance without bridging of liquid.

19. A cooling element including a plurality of

inclined conduit sections located one above another so that liquid will flow along the exterior of said sections and drop from one upon another, wall structure forming a closed space around said conduit sections equidistant from diametrically opposite sides of the conduit forming said sections, means for delivering liquid refrigerant above said conduit sections members for conducting gas to the upper part of and from the lower part of said space, and connections for flow of fluid to be cooled interiorly of said conduit sections, the distance of said wall structure from said conduit sections being such as to provide a minimum diffusion distance without bridging of liquid.

20. A refrigeration system including structure forming a substantially annular place of evaporation, means for conducting liquid refrigerant fluid to said place of evaporation, members for conducting inert gas to and from said place of evaporation, and a member for conducting liquid in contact with the gas and located centrally in said place of evaporation, said structure and members being spaced to provide a minimum diffusion distance without bridging of liquid.

21. Refrigeration apparatus of an absorption type including a condenser, an absorber, means for conducting water in cooling relation with said absorber, means for causing flow of air in contact with said condenser, and means for flowing water which has been heated by said absorber and conducting the heated water into contact with said condenser, whereby the water is cooled by evaporation into the air stream to increase its capacity for cooling the condenser.

22. In the art of producing refrigeration with the aid of a system having an absorber and a condenser, that improvement which consists in flowing water in cooling relation to the absorber, and utilizing the water which has been heated by the absorber for evaporative cooling of the condenser.

23. An absorption refrigeration system including structure forming a substantially annular place of absorption, means for conducting absorption liquid to said place of absorption, means for conducting gas to and from said place of absorption, and a member for conducting absorption liquid in contact with gas and arranged in said place of absorption so that liquid flows substantially concentrically in said annular place in contact with two annular streams of gas.

24. Refrigerating apparatus including a generator for expelling refrigerant from solution, a condenser connected to receive and adapted to condense the expelled refrigerant, a principal evaporator connected to receive the condensed refrigerant from the condenser for primary evaporation, said evaporator including an outer relatively wide vessel, a pipe coil situated relatively close to the inside wall of said vessel, an inner wall spaced inward of said pipe coil equal to its spacing from the outer wall, a liquid holder and spreader above said pipe coil for equalizing distribution of liquid refrigerant thereon, an absorber, means to circulate absorption liquid between the generator and the absorber, means to conduct weak gas from the absorber and introduce the same into said evaporator, and means to conduct rich gas from the evaporator to the absorber.

25. Refrigerating apparatus including a generator for expelling refrigerant from solution, a condenser connected to receive and adapted to condense the expelled refrigerant, a principal evaporator connected to receive the condensed re-

frigerant from the condenser for primary evaporation, said evaporator including an outer relatively wide cylinder, a pipe coil situated relatively close to the inside wall of said cylinder, an inner cylinder spaced inward of said pipe coil equal to its spacing from the outer wall, said inner cylinder having a diameter at least equal to several times the width of the space between the cylinders, a liquid holder and spreader above 5 said pipe coil for equalizing distribution of liquid refrigerant thereon, an absorber, means to circulate absorption liquid between the generator and the absorber, means to conduct weak gas from the absorber and introduce the same into 10 said evaporator, and means to conduct rich gas from the evaporator to the absorber.

26. Refrigerating apparatus including a generator for expelling refrigerant from solution, a condenser connected to receive and adapted to 20 condense the expelled refrigerant, a principal evaporator connected to receive the condensed refrigerant from the condenser for primary evaporation, said evaporator including an outer relatively wide vessel, a pipe coil situated relatively 25 close to the inside wall of said vessel, an enlarged conduit portion forming an inner wall spaced inward of said pipe coil equal to its spacing from the outer wall, a liquid holder and spreader above said pipe coil for equalizing distribution of liquid 30 refrigerant thereon, an absorber, means to circulate absorption liquid between the generator and the absorber, means to conduct weak gas from the absorber to and through said enlarged conduit portion and into said evaporator, and 35 means to conduct rich gas from the evaporator to the absorber.

27. Refrigerating apparatus including a generator for expelling refrigerant from solution, a condenser connected to receive and adapted to 40 condense the expelled refrigerant, a principal evaporator connected to receive the condensed refrigerant from the condenser for primary evaporation, said evaporator including an outer relatively wide vessel, a pipe coil situated relatively 45 close to the inside wall of said vessel, an inner wall spaced inward of said pipe coil equal to its spacing from the outer wall, a liquid holder and spreader above said pipe coil for equalizing distribution of liquid refrigerant thereon including a 50 wick having a horizontal lower edge, an absorber, means to circulate absorption liquid between the generator and the absorber, means to conduct weak gas from the absorber and introduce the same into said evaporator, and means to 55 conduct rich gas from the evaporator to the absorber.

28. Refrigerating apparatus including a generator for expelling refrigerant from solution, a condenser connected to receive and adapted to 60 condense the expelled refrigerant, a principal evaporator connected to receive the condensed refrigerant from the condenser for primary evaporation, said evaporator including an outer relatively wide vessel, a pipe coil situated relatively 65 close to the inside wall of said vessel, an inner wall spaced inward of said pipe coil equal to its spacing from the outer wall, a liquid holder

and spreader above said pipe coil for equalizing distribution of liquid refrigerant thereon, an absorber including an outer relatively wide vessel, a pipe coil situated relatively close to the inside wall of said last-mentioned vessel, an inner wall spaced inwardly of said pipe coil equal to its spacing from the outer wall and a liquid holder and spreader above said last-mentioned pipe coil, means to circulate absorption liquid between the generator and the absorber, means to conduct 10 weak gas from the absorber and introduce the same into said evaporator, and means to conduct rich gas from the evaporator to the absorber. 5

29. Refrigerating apparatus including a generator for expelling refrigerant from solution, a 15 condenser connected to receive and adapted to condense the expelled refrigerant, a principal evaporator connected to receive the condensed refrigerant from the condenser for primary evaporation, an absorber, said absorber including an 20 outer relatively wide vessel, a pipe coil situated relatively close to the inside wall of said vessel, an inner wall spaced inwardly of said pipe coil equal to its spacing from the outer wall, a liquid 25 holder and spreader above said pipe coil for equalizing distribution of liquid refrigerant thereon, means to circulate absorption liquid between the generator and the absorber, means to conduct weak gas from the absorber and introduce the same into said evaporator, and means to conduct 30 rich gas from the evaporator to the absorber.

30. In refrigerating apparatus of the kind in which refrigerant diffuses into inert gas, a vessel including means for flow of a first liquid having a surface, means to flow a second liquid on said surface, said first means being formed so that said second liquid drips from part to part of said surface, means to circulate inert gas adjacent said surface, said vessel including a wall limiting the path of flow of inert gas adjacent said surface, said surface and wall being spaced to provide a minimum diffusion distance without bridging of liquid, said surface and wall being mutually irregular to provide turbulence, and members connected to said vessel to form a system for circulation of liquid and gas. 40 45

31. In a refrigerating system of the kind employing an inert gas, structure providing a path of flow for inert gas including a wall, a conduit in said path of flow of inert gas connected for flow of liquid therethrough, means to cause liquid to flow on the exterior of said conduit, said conduit being formed so that liquid flowing on the exterior thereof drips from part to part of said conduit, said conduit being relatively close to said wall to provide a gap therebetween in said path of flow of inert gas without bridging of such gap by liquid flowing over the exterior of said conduit and dripping from part to part thereof, and a member on the opposite side of said conduit from said wall and relatively close to said conduit to provide a gap therebetween in said path of flow of inert gas without bridging of the last-mentioned gap by liquid flowing over said conduit and dripping from part to part thereof. 55 60 65

ALBERT R. THOMAS.
